UNITED STATES PATENT OFFICE.

LEWIS D. TIBBETS, OF CLAYTON, WASHINGTON.

INNER TUBE FOR TIRES.

1,306,130.

Specification of Letters Patent. Patented June 10, 1919.

Application filed November 13, 1918. Serial No. 262,334.

To all whom it may concern:

Be it known that I, LEWIS D. TIBBETS, a citizen of the United States, residing at Clayton, in the county of Stevens, State of Washington, have invented certain new and useful Improvements in Inner Tubes for Tires; and I do hereby declare the following to be a full, clear, and exact description of the invention, such as will enable others skilled 10 in the art to which it appertains to make and use the same.

The invention relates to a tire and more particularly to the class of inner tubes for tires used on automobiles, motorcycles or the 15 like.

The primary object of the invention is, the provision of an inner tube of this character wherein the body thereof is made to assure maximum durability and to avoid blow-outs, 20 punctures or the like, the tube being possessed of the requisite resiliency and in the use thereof, will assure longevity and increased mileage.

Another object of the invention is, the 25 provision of an inner tube of this character, wherein the construction thereof is novel in form to avoid the necessity of inflation with air, yet it will possess the required resiliency, lightness in weight and strength.

A further object of the invention is, the 30 provision of an inner tube of this character, which is extremely simple in construction and inexpensive to manufacture.

With these and other objects in view, the 35 invention consists in the features of construction, combination and arrangement of parts as will be hereinafter fully described, illustrated in the accompanying drawing and pointed out in the claims hereunto appended.

In the accompanying drawing:

Figure 1, is an elevation of an inner tube constructed in accordance with the invention.

Fig. 2, is a fragmentary vertical longitudinal sectional view through the joined ends of the tube.

Fig. 3, is a sectional view on the line 3—3 of Fig. 2.

Fig. 4, is a fragmentary elevation showing the ends of the tube separated from each other.

Similar reference characters indicate corresponding parts throughout the several 55 views in the drawing.

Referring to the drawing in detail, the in-

ner tube comprises a tubiform body 5 of the required size in cross sectional diameter and is made from a plurality of strands of spring wire 6, interwoven or laced in close crisscross relation to each other to give the appearance of braiding, so as to leave in the finished tube practically no open space between the strips or interstices, whereby pebbles or other foreign matter may become embedded between the strands or work through the tube. The tube formed by the body 5 is curved to conform with the periphery of the rim of a wheel and the strands of wire possesses the requisite resiliency or yieldability to render 70 the tube flexible and resilient.

One end of the tube is formed with a contracted or reduced extremity 7 having a reinforcing band 8, while the other end of the tube is of a size corresponding to the cross 75 sectional area or diameter of the body 5 and is reinforced through the medium of a band 9 constituting a female extremity for the reception of the contracted extremity formed by the band 8 constituting the male extremity which is adapted to fit within said female extremity which slips over the male extremity and abuts a shoulder 10 formed by the contraction of said extremity 7. These 80 interfitted extremities 8 and 9 are brazed or welded together or otherwise permanently fastened to provide a continuous endless tube.

The reinforcing bands on the ends of the tube are engaged or fastened to the body 5, 85 in any desirable manner to provide a unitary connection therewith.

It is of course to be understood that the circumferential size of the tube can be varied and also the cross sectional diameter thereof 90 corresponding to the required use of the inner tube in various sizes of tires and this tube is made by the use of suitable machinery for the weaving of the strands of the wire 6 and the finishing of the tube.

The tube has too, the advantages of the rubber pneumatic inner tube and overcomes the disadvantages of the latter.

What is claimed is:

1. An inner tube comprising a plurality 105 of wire strands woven together to provide a tubiform body having a contracted end and an opposite end of a normal size corresponding to the cross sectional diameter of the body and adapted to be fitted over the 110 contracted end, and reinforcements on said ends and united to each other.

2. An inner tube comprising a plurality of wire strands woven together to provide a tubiform body having a contracted end and an opposite end of a normal size corresponding to the cross sectional diameter of the body and adapted to be fitted over the contracted end, and reinforcements on said ends and united to each other, the contracted end of the body forming a shoulder for abutment by the normal other end of the said body.
3. An inner tube for tires comprising a tubular woven body of uniform diameter having one end reduced at right angles to

form a shoulder facing the other end and a reduced portion, a band on the reduced end, 15 and a band in the other end engaged over the reduced end and the band thereon to abut said shoulder, said bands being secured together.

In testimony whereof, I affix my signature, 20
in the presence of two witnesses.

LEWIS D. TIBBETS.
